UNITED STATES PATENT OFFICE.

JOSEPH S. APFEL, OF NEW YORK, N. Y.

DESIGN FOR A BOUDOIR-LAMP OR THE LIKE.

58,864.

Specification for Design.

Patented Sept. 6, 1921.

Application filed January 26, 1921. Serial No. 440,240. Term of patent 7 years.

To whom it may concern:

Be it known that I, JOSEPH S. APFEL, a citizen of the United States of America, residing at New York city, county and State of New York, have invented a new, original, and ornamental Design for a Boudoir-Lamp or the like, of which the following is a specification, reference being had to the accompanying drawing, which represents a side elevation of a boudoir lamp embodying my new design.

I claim:

The ornamental design for a boudoir lamp or the like, as shown.

Signed at New York city, N. Y., this 25th day of January, 1921.

JOSEPH S. APFEL.

Witnesses:

MAURICE BLOCK,
EDUARD A. JARVIS.
